N. F. RICE

VALVE PAD FOR PNEUMATIC TIRES

Filed Oct. 16, 1922

FIG. 1

FIG. 2

FIG. 3

INVENTOR
Nathan F. Rice

BY Jones, Ellington, Ames & Schold
ATTYS.

UNITED STATES PATENT OFFICE.

NATHAN F. RICE, OF CHICAGO, ILLINOIS.

VALVE PAD FOR PNEUMATIC TIRES.

Application filed October 16, 1922. Serial No. 584,761.

To all whom it may concern:

Be it known that I, NATHAN F. RICE, a citizen of the United States, residing at Chicago, in the county of Cook and State of Illinois, have invented new and useful Improvements in Valve Pads for Pneumatic Tires, of which the following is a full, clear, concise, and exact description, reference being had to the accompanying drawing, forming a part of this specification.

My invention relates to valve pads for pneumatic tires. The invention is in the nature of an improvement on or modification of the construction shown in my Patent No. 1,395,731, dated November 1, 1921.

In the construction shown in my patent, means were provided for preventing injury to the pneumatic tube at the point where the valve stem extends through the tube, this being provided by means of a rubber pad having a metal plate embedded therein, the plate having an opening through which the valve stem passes, the valve stem being provided with clamping members which embrace the pad and the portion of the tire through which the stem passes, the plate serving to prevent that portion of the pad and tube embraced by the clamping member from being squeezed out from between the clamping members when the clamping pressure was applied, or when the tire was subjected to use.

The construction shown in my patent answers the purpose for which it was intended, that is, it prevents the pad from being squeezed out from under the clamping members, but as the edge of the hole in the metal plate through which the stem extended was unyielding, the hole had to be made considerably larger than the diameter of the stem, in order to permit the ready insertion of the stem through the pad. The object of my present invention is to provide a substitute for the plate which will have all the advantages of the plate and in addition will permit the ready insertion of the valve stem through the pad and at the same time will have an opening therethrough which will be of substantially the same diameter as the diameter of the valve stem, thus bringing the element which prevents squeezing out of the pad, up close to the valve stem.

Further objects will appear from the detailed description to follow and from the appended claims.

In the drawings in which an embodiment of my invention is shown—

Figure 1 is a sectional view showing a tube in position with respect to the wheel, and the valve stem and pad in place;

Fig. 2 is a view of the pad, parts being broken away to show the interior construction; and

Fig. 3 is a section on the line 3—3 of Fig. 2.

Referring now to the drawings in detail, the construction shown therein comprises the inner tube 10 which may be of any usual or suitable construction, the valve stem 11, the head 12 which is inserted through an opening 13 into the inner tube 10, and a demountable rim 14 and wheel portion 15 which may be of any usual or suitable construction.

A pad 16 is secured to the tube 10 at the point where the valve stem 11 extends through it, this pad being provided in order to prevent injury to the tube at this point. The main feature of this pad is the insert 17 of wire mesh. This mesh insert has an opening at 18 which is just large enough to permit the valve stem 11 to be inserted therethrough. As a matter of fact, it may be made somewhat smaller than the valve stem, so that the stem will have to be forced through the opening, the edges of the mesh at the opening yielding slightly to permit this insertion. While the wire mesh insert will yield slightly to permit the insertion of the valve stem it will nevertheless prevent the edges of the pad adjacent the valve stem from being squeezed out between the head of the valve stem 12 and the clamping member 18 when the latter is tightened up.

This metal mesh insert may be secured in the pad by placing it between two layers of rubber, and then vulcanizing the rubber together. The layers of rubber are vulcanized together through the meshes of the wire insert so that a very tough durable construction is secured, the construction being substantially as though the wire mesh were embedded in an integral body of rubber. If desired, the pad may be further toughened by providing inserts of fabric as indicated at 19 and 20. The stem may be secured in position on the wheel by means of the usual securing nut 21. The pad may be secured to the inner tube 10 by vulcanizing.

It will be seen that I have thus provided a construction which has the advantages of

the construction shown in my previous patent, in that the edges of the pad and tube adjacent the stem cannot be squeezed out from underneath the clamping members, and in which the member which accomplishes this desirable result can be made to extend close up to the valve stem itself. The wire mesh furthermore has more flexibility than the metal plate, which enables it to accommodate itself to the tube to which it is attached. The wire mesh enables the two layers of rubber between each of the plates to be readily vulcanized together through the mesh of the fabric which gives a very tough construction.

Having thus described my invention, what I claim as new and desire to secure by Letters Patent of the United States is—

1. A pneumatic tube having an opening 20 therein, a valve stem passing through said opening, and a pad for preventing injury to said tube adjacent said stem, said pad comprising a layer of flexible yielding material and a layer of woven metal having an opening through which said stem passes.

2. A pneumatic tube having an opening therein, a valve stem passing through said opening, and a pad for preventing injury to said tube adjacent said stem, said pad comprising a body of flexible yielding material, and a layer of woven metal embedded in said body, and having an opening through which said stem passes.

3. A pneumatic tube having an opening 35 therein, a valve stem passing through said

opening, and a pad for preventing injury to said tube adjacent said stem, said pad comprising two layers of flexible yielding material, and a layer of woven metal between said layers of flexible material, said layers 40 of flexible material being vulcanized together through the mesh of said woven metal layer, said woven metal layer having an opening through which said valve stem extends.

4. A pneumatic tube having an opening 45 therein, a valve stem passing through said opening, and a pad for preventing injury to said tube adjacent said stem, said pad comprising a body of flexible yielding material, and a layer of woven metal embedded in said body, said body being vulcanized to said tube, and said layer of woven metal having an opening through which said valve 50 stem extends.

5. A pneumatic tube having an opening therethrough, a valve stem passing through said opening, and a pad for preventing injury to said tube adjacent said stem, said pad comprising a body of flexible yielding material, and a layer of woven metal embedded in said body, said layer of woven metal having an opening through which said valve stem extends, said valve stem being provided with clamping members 60 embracing the pad and the portion of the tube through which the valve stem extends.

In witness whereof, I have hereunto subscribed my name.

NATHAN F. RICE.
